PISTON RING GRINDER

Rudolph F. Flora, Muskegon, Mich., assignor to
The Clover Foundry Company, Muskegon,
Mich., a corporation of Michigan

Application September 16, 1942, Serial No. 458,482

5 Claims. (Cl. 51—129)

This invention relates to a grinder primarily designed for rough or snag grinding of piston ring castings.

It is a substantially universal practice to manufacture piston rings from individual ring castings, finishing each casting to provide a completed piston ring, though in some cases ring castings are produced to make two and at times three finished rings from one casting. Generally such ring castings are of an out-of-round form, being cast from patterns which were initially circular in form then split at one side and a segment inserted in the gap. A portion of the ring casting produced from such pattern is removed to correspond with said segment insert, whereby when the piston ring is finished it normally is open a distance at the gap which, upon being closed, causes the ring to take a circular form and produces an inherent tension in the ring causing it to press outwardly against a cylinder wall. Other rings, known as dead rings, may be made from patterns of substantial circular form so that the castings are nearly if not truly circular.

In all of such casting of ring castings, whether for individual rings, or two or more of the rings from a single casting and whether in an out-of-round or circular form, the metal flowing into the mold recesses reaches said recess through gates extending outward from a central sprue into which the molten metal is poured. When the molding sand is shaken loose from the completed castings there is a tree of castings having a central trunk produced by the molten metal remaining in the sprue and branches from the trunk ending in ring castings which are connected with the tree by the molten metal which has filled and solidified in the gates. The ring castings are broken from the tree easily and readily but leaving rough projections where such connections between castings and central tree are broken. Also in the castings of rings a hard and tough outside skin is produced around the castings where the molten metal contacts with the sides of the recess of the sand mold making a relatively rough surface and one which has to be initially removed before finishing the rings. Of course all mold recesses are not perfect and there may be and frequently are projections extending from the ring castings because of minor defects in the molds.

The first operation generally performed upon a ring casting is to rough or snag grind it. In early practice this was done by hand operation, workmen picking up the castings singly and bring-

ing them against the surface of a rapidly rotating grinding wheel to remove snags, portions of the gate projections which were left and as much of the outer surface of the ring casting as seemed necessary. This individual grinding by hand has long since been superseded by quantity production machines. The present invention is directed to a machine for rough or snag grinding the outer curved surface of a ring casting and which is usable for ring castings of various sizes without changing the setup of the machine to any material extent, which will operate with round casting or out-of-round castings and also with individual ring castings or castings from which two or more rings are to be made.

Objects and purposes of the present invention are to provide a machine in which rough or snag grinding of piston castings as specified may be accomplished with great rapidity to provide increased production; wherein grinding wheels may be utilized to their fullest extent and not be thrown away upon wearing down at their outer peripheral surfaces as is now required with most grinding machines used for such purposes; in which the generation of heat is minimized; peening of the casting from chattering of the rings against the grinding wheel reduced and minimized with less tendency to provide grooves in the grinding wheel which changes contour and requires frequent dressing; less ring breakage while grinding, a lesser tangential grinding pressure upon the castings; and with the peripheries of the ring castings maintained straight and normal to the sides thereof.

With my invention also the grinding wheels may be quickly dressed without time consumed in changing the setup when grinding is resumed; the grinding wheel may be quickly changed with no re-setup required upon resumption of grinding; and with more room to place the rings in grinding position and to remove them after grinding with correspondingly less danger to an operator of the machine. These and other objects of the invention not at this time specifically stated will be apparent upon an understanding of the invention from the following description, taken in connection with the accompanying drawings, in which.

Fig. 1 is a front elevation of a grinding machine made in accordance with my invention.

Fig. 2 is an elevation looking at the machine from the left in Fig. 1.

Fig. 3 is a fragmentary elevation of the upper part of the machine with some parts in section looking at the machine from the right in Fig. 1.

Fig. 4 is an elevation and section showing the ring castings upon the carrying arbor therefor as they are brought against the side of a grinding wheel, and,

Fig. 5 is a vertical section through Fig. 4 between the ends of the arbor and looking to the right.

Like reference characters refer to like parts in the different figures of the drawings.

The grinding machine includes a supporting casting 1 for a shaft 2 upon which a grinding wheel 3 is secured, the shaft being power driven in any suitable manner at high speed in the operation of the machine. A cylindrical member 4 is permanently connected integrally or otherwise with the casting 1 below the grinding wheel, on which a bracket 5 is mounted by means of a split collar 6 tightened upon the member 4 by set screws at a desired position.

The bracket 5 at its upper side is provided with spaced apart upwardly extending lugs 7 upon which a ring arbor carrying support 8 is tiltably mounted by means of a shaft 9 as shown, whereby said support 8 may be tilted about the axis of the shaft 9 toward or away from the outer flat side of the grinding wheel. The support 8 at one side has an upwardly extending arm 10 terminating in a journal 11 while at the other side it is provided with an upwardly extending arm 12 to the upper end of which a gate 13 is pivotally mounted by a pivot pin 14 as best shown in Fig. 1.

An arbor is mounted in the journal 11 including a shaft section 15 rotatably mounted in said journal from which an arbor 16 extends to lie parallel to the outer face of the grinding wheel. The arbor is of smaller diameter than the shaft section 15 thereby providing a continuous annular shoulder 17 between the arbor and the adjacent end of the shaft. The outer end of the arbor is provided with a head, as indicated at 18, larger in diameter than the arbor 16 where it connects with the arbor forming a second continuous annular shoulder adjacent the outer end of the arbor. At the end of the journal 11 a plate 19 is permanently secured of the form best shown in Fig. 5. A plurality of the ring castings 20 are placed over the arbor by moving the gate 13 to the dotted line position shown in Fig. 1, then returning the gate to its operative position, said gate having an opening for the reception of the head 18 (Fig. 4).

At the outer end of the arbor shaft a pulley 21 is secured, driven by an endless belt 22 which also passes around a pulley 23 which is connected with a second pulley 24 to rotate therewith both about the axis of the shaft 9. The pulley 24 is driven by an endless belt 25 which passes around a pulley 26 secured to the shaft of an electric motor 27 mounted on a suitable bracket 27a extending from the supporting casting 1.

When the motor is operating the arbor 16 is driven with that portion of its periphery adjacent the grinding wheel 3 traveling in the same direction but at considerably less speed. The location of the arbor is above the horizontal diameter of the grinding wheel 3 with the axis of said arbor substantially parallel to the horizontal. Such position of the arbor may be changed by adjustment of the bracket 5 about the member 4. When the arbor carrying support 8 is moved toward the grinding wheel the ring castings are brought against the outer side face of the wheel and said ring castings take the

position shown in Fig. 5, pressing against the outer side of the grinding wheel and against the arbor with the end ring casting nearest the plate 19 coming against the shoulder 17. With the rotation of the grinding wheel in the direction of the arrow in Fig. 1, the tendency is to move the castings to the right (Fig. 1) so as to hold the end casting always against said shoulder 17. The ring castings being disposed above the horizontal diameter of the grinding wheel, the action of the wheel upon the outer curved surface of the ring castings is what may be termed a diagonal movement across from one side to the other of the ring castings. Simultaneously the ring castings are rotated by the rotation of the arbor coupled with their pressure against the grinding wheel.

The movement of the arbor toward the grinding wheel is controlled by an adjustably mounted pneumatic mechanism shown in Fig. 3. A guide 28 is secured to a side of the main casting 1 upon which a block 29 is slidably mounted and adjusted by means of a hand operated screw 30 as shown in Fig. 3. At one end the block 28 is provided with an upwardly extending arm. An air cylinder 31 at one end has a projecting fork 32 pivotally connected by means of a pivot pin 33 to the upper portion of said arm. A piston 34 within the cylinder has a piston rod 35 connected therewith which passes through one end of the cylinder and has a pivotal connection with a lug 36 extending from the arbor supporting member 8, substantially midway between its upper and lower ends. Compressed air is carried into the cylinder through a conduit 37 to transmit its force against said piston to move it and move the arbor toward the grinding wheel.

The operation of the motor 27 is controlled by an automatic mercury switch 38 mounted at a side of the arbor support 8 with the usual cable 39 carrying the circuit wires from said switch to the motor and source of electric power. On the tilting of the arbor carrying support to its operative position, shown in Figs. 2 and 3, the mercury switch is automatically closed thus energizing the motor 27 for operation. On moving the arbor and its support away from the wheel to the dotted line position shown in Fig. 2, said switch is automatically disconnected and the motor stops. The outward movement to said dotted line position is controlled as to its extent by stop lugs 40 at the lower part of the arbor carrying support 8 which comes against the bracket 5 when a predetermined outer position is reached. It is in this position with the arbor at rest and motor 27 not operating that the arbor is loaded with ring castings for processing and the processed castings removed from the arbor after they have been ground.

In the operation, with the motor 27 at rest the arbor and its support are at the dotted line position shown in Fig. 2; the gate 13 is turned about the pin 14 to the dotted line position shown in Fig. 1, the desired number of ring castings placed on the arbor and the gate turned to its upper position. The gate may be provided with a yielding spring which will normally hold it in operative position. Compressed air is then directed into the conduit 37 by means of a suitable valve control, moving the piston 34 to the right (Fig. 3) and bringing the ring castings against the side of the grinding wheel. At the same time the electric circuit in which the motor 27 is positioned will be closed by the automatic closing of the mercury switch 38. The grinding wheel rotates con-

tinuously at high speed. The control of the amount of grinding at the outer curved surface of the rings is through the adjustment effected by the adjusting screw 30. The outward movement of the arbor and its support to the dotted line position shown in Fig. 2 is performed manually, opening the control valve for the compressed air to exhaust the air in the cylinder 31 and permit such outward movement with a simultaneous movement of the piston 34 to the left (Fig. 3). In this position the gate 13 is turned to permit the removal of the processed rings and their replacement by another quantity of ring castings to be processed.

With this construction of grinding machine, ring castings of many different sizes and diameters may be rough or snag ground at their outer curved surfaces without substantial change in setup of the machine, at least no more than the adjustment change required for a different radial thickness of ring castings which will be taken care of by the hand operation of adjusting screw 30.

The operation is relatively simple and production of rough ground rings is rapid. The diagonal grind across the peripheries of the rings maintains the outer curved surface of the ring normal to the sides thereof without rounding or concaving of the ring surface. When required the grinding wheel may be quickly dressed without change in the machine setup. The grinding wheel may be used almost completely. It is evident also that by simple modification two grinding wheels one at each end of the shaft 2 may be supplied each with an arbor mechanism, or other alterations of an equivalent nature made to provide two grinders on one base or supporting structure. Ring castings of a wide range of diameters may be used without variation of the ring set up. The diagonal grinding also tends to hold the rings on the arbor at the same positions with the ends ring bearing against the stop provided by the shoulder at 17. The control of the pressure of the ring castings against the grinding wheel is accomplished through manual control of passage of compressed air into the cylinder which may be controlled as to quantity, may be shut off or very nearly shut off and otherwise readily controlled for the best results whereby heat generated while grinding is at a minimum and the grinding pressure controlled thereby avoiding ring breakage.

The mechanism described as an embodiment of the invention may be altered in specific detail. For example, while the adjusting screw 30 for the block 29 and the end of the piston rod 35 coming against the end of the cylinder 31 effects a stop for the grinding of the castings, such stop is not absolutely necessary as the control of rough grinding is obtained readily by controlling the compressed air flow to the cylinder by manual operation of the air control valve. The valve may be of a three-way character likewise and air alternately entered at either end of the cylinder and exhausting from either end of the cylinder to the atmosphere in moving the arbor carrying support from loading to grinding position and back. The compressed air may be controlled to provide a cushion against which the piston acts with a yielding pressure when required by the engagement of gate projections or other projections against the grinding wheel.

This machine has been produced and is used regularly in rough and snag grinding of piston rings and has proved exceptionally serviceable in all respects.

The invention is defined in the appended claims and is to be considered comprehensive of all forms of structure coming within their scope.

1. claim:

- 5 1. In a grinding machine, a driven grinding wheel, a rotatably mounted arbor over which a plurality of ring castings are placed, said arbor being of less diameter than the interior diameter of the castings, said arbor having a free end and a shoulder between its ends against which the first ring casting placed on the arbor is adapted to engage, a movably mounted member on which said arbor is rotatably mounted, means for moving said member and arbor toward a side of the grinding wheel to bring the ring castings into grinding engagement with the side thereof the axis of the arbor substantially paralleling a diameter of the grinding wheel and spaced a distance from said diameter and means for causing said arbor to be positively and continuously driven on movement of the arbor and castings to such position, in the same direction as the grinding wheel but at less speed.
- 10 2. In a grinding machine, a driven grinding wheel located with its sides in substantially vertical planes, a rotatably mounted arbor, a movably mounted member on which said arbor is mounted, the arbor having a free end portion extending to one side of said member over which ring castings are adapted to be freely placed, said arbor between its ends having a continuous annular shoulder against which the first ring casting placed over the arbor engages, a portion thereof being engaged by a portion of the adjacent edge of the ring casting, means for driving said arbor, means for moving said arbor carrying member toward a vertical side of the grinding wheel after ring castings have been placed thereon and means for effecting a continuous driving of said arbor at less speed and in the same direction as the grinding wheel when said member is thus moved toward the grinding wheel and for stopping said driving of the arbor when moving away from the wheel, said arbor being spaced a distance from the plane of the horizontal diameter of said wheel.
- 15 3. In a machine of the class described, a driven grinding wheel having a vertical grinding face, an arbor carrying member mounted to be moved toward or away from the face of the grinding wheel, a shaft rotatably mounted on said member having an arbor at one end thereof over which ring castings are adapted to be located when said member is away from the grinding wheel, an electric motor, means for driving said shaft from said motor, means for starting said motor upon movement of the arbor carrying member toward the grinding wheel and for stopping operation of said motor on movement of said member away from the grinding wheel, said arbor being of less diameter than the shaft providing a shoulder at their juncture against which the innermost ring casting of the castings placed over the arbor engages at its inner side and said arbor being located in a position above the horizontal diameter of said grinding wheel whereby on engagement of the grinding wheel and rotation thereof in a direction toward the upper portions of said ring castings on the arbor, said castings are moved in a direction to force the innermost casting against said shoulder.
- 20 4. In a grinding machine, a driven grinding wheel mounted to turn about a horizontal axis and having a vertical grinding face, a movably mounted support located at one side of the face of said grinding wheel and movable toward or

away from it, said support having a journal thereon, a shaft rotatably mounted in said journal, said shaft having an end arbor portion of lesser diameter than the diameter of the shaft providing an arbor over which a plurality of piston rings may be freely placed, there being a continuous annular shoulder between said arbor portion and the larger portion of the shaft, whereby the first ring casting placed over said arbor portion engages at a part of its adjacent edge against a part of said shoulder, the arbor portion of said shaft being of less diameter than the interior diameter of the piston ring casting placed thereover, and means for driving said shaft when it is moved with its movably mounted support toward said face of the grinding wheel, the diameter of said

shaft being located to a side to the axis of rotation of the diameter of the grinding wheel and in parallelism to the diameter of the grinding wheel.

5. A construction having the elements in combination defined in claim 4, said movably mounted support for said arbor shaft being located with respect to the grinding wheel so that the journal is substantially outside of the periphery of the grinding wheel, and a gate movably mounted on 10 said support adapted to be moved into a position in substantial parallelism to the last ring casting placed over said arbor portion of the shaft but out of contact engagement therewith or to be moved to a second position away therefrom.

RUDOLPH F. FLORA.
